ATTACHMENT FOR BOOKKEEPING MACHINES

Joseph H. Loeb, Morgan City, La.

Application December 16, 1932, Serial No. 647,632

8 Claims. (Cl. 197—127)

This invention relates to an attachment for bookkeeping machines.

Bookkeeping machines are adapted for posting, proving and establishing a complete journal in one operation, and are equipped with a front feed carriage which permits the posting of a customer's statement, ledger and proof journal, and other items. In such machines a platen is employed around which the loose-leaf ledger paper is placed after having been taken from the books for the posting of the various items. In such machines, however, it is difficult without the exercise of great care to place the paper in position so that other items may be added in sequence to the last posted on the sheet. Various means have been employed for accomplishing this result but such means are still dependent upon the skill of the operator rather than upon any mechanical means embodied in the machine.

It is an object of the present invention to provide an attachment for bookkeeping machines which will automatically position the sheet in a bookkeeping machine for the application of additional items after the sheet had been previously used.

A further object of the invention is the provision of an attachment for bookkeeping machines in which the usual operating lever for the platen will automatically punch holes in the side of the sheet so that a plunger or stop will engage the opening thus formed and not only provide for a line for line positioning of the sheet but will determine the exact position of a sheet when new items are to be applied thereto.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

In the drawings:

Figure 1 is a plan view of a bookkeeping machine partly in section.

Figure 2 is a vertical section showing a construction which illustrates the principles of my invention.

Figure 3 is a similar section showing a partial operation of the device.

Figure 4 is a fragmentary vertical section similar to Figs. 2 and 3 showing another position of the stop.

Figure 5 is a vertical section showing the crank for operating the stop.

Figure 6 is a vertical section through the lever showing the hinged sleeve.

Figure 7 is a vertical section showing the punching device applied to a platen.

Figure 8 is an enlarged fragmentary vertical section showing the punching device and stop mechanism in operative relation.

Figure 9 is an enlarged horizontal section of the stationary sleeve which supports the stop.

Figure 10 is a fragmentary plan view of a sheet of paper employed in the device.

Figure 11 is a plan view, partly in section, of the modified form of the construction.

Figure 12 is a vertical section taken along the line 12—12 of Figure 11.

Figure 13 is a similar section showing an angular movement of the operating parts.

Figure 14 is a vertical section showing the platen and punching device.

Figure 15 is a vertical section taken along the line 15—15 of Figure 11.

Figure 16 is a fragmentary view in perspective of one end of an operating lever.

Figure 17 is a vertical section taken along the line 17—17 of Figure 15, and

Figure 18 is a fragmentary plan view of a sheet of paper employed in the modified form.

Referring more particularly to the drawings, 30 10 designates a frame which forms part of the bookkeeping machine and is adapted to support certain elements which also form part of the bookkeeping machine.

A platen 11 is connected to a shaft 12 and this shaft is connected to a stub shaft 13 by means of a clutch member which will be described presently. A shaft 16 is provided with a manipulating member 13 for manually rotating the platen 11 for properly positioning a sheet of paper.

A gear 16 is loosely mounted upon a stub shaft 17 carried in bearings 18 on the frame 10.

A bell crank lever, generally designated by the numeral 20, has an operating arm 21 provided with a manipulating handle 19 which is manually actuated. A short arm 22 forms part of the bell crank lever. This bell crank lever is loosely mounted on the shaft 17. The upper end of the arm 21 is provided with a sleeve 23 in which is slidably mounted an arm 24. A spring 25 on the arm 24 retains the arm 24 in a predetermined position. A pawl 26 on the outer end of the arm 24 is adapted to engage the teeth of the gear 16. A spring 27 is connected between the outer free end of the arm 21 and a fixed part 28 of the book-

keeping machine so that the spring will always tend to move the arm 21 to the position shown in Fig. 2. A spring 29 maintains the pawl 26 in position for engagement with the teeth of the gear 16.

The short arm 22 is provided with a depending rod 30 which carries at its lower free end a hinged pawl 31 adapted to engage a crank 32 formed integrally with a shaft 33 mounted in a bearing 34. 10 A second crank 35 carried by the shaft 33 is adapted to engage an enlarged free end 36 of a rod 37 slidably mounted in bearings 38 on a base member 39.

An arm 40 projects laterally from the rod 37 15 and is provided with a pin 41 adapted to be received within a perforation 42 previously formed in a sheet of paper 43 which is adapted to be moved by a platen 44. The pin 41 is provided with a ball 45 at its lower end which is capable of being revolved when sliding over the surface of the paper 43.

The paper 43 is the sheet employed in book-keeping systems which is placed in the bookkeeping machine and certain items are applied to the 25 lines of the sheet by means of the usual typewriting mechanism (not shown). This sheet engages the outer surface of the platen 44 and is frictionally moved upwardly for the application of the various items by the typewriting apparatus.

A sleeve 46 is received by a reduced end of the platen 44 so that the outer surface of the sleeve is flush with the outer surface of the platen. This 35 sleeve is held stationary against rotation while the platen 44 is rotated. This sleeve is provided with a perforation 47 which receives the pin 41 when the perforation and cut-out portion 42 align with the perforation 47, thereby maintaining the sheet of paper against movement.

A spring 48 is connected with the arm 40 and with the fixed part 49 and is adapted to maintain the pin 41 in engagement with the sheet 43 when items are typed on the sheet.

The arm 24 is slidably mounted in the sleeve 23 and this sleeve is pivotally connected to the arm 21, as shown at 50, so that the arm 24 may not only be reciprocated but may be rocked by the spring 29 for moving the pawl 26 into engagement with the teeth of the gear 16.

The outer end of the arm 24 is sheared off at an angle, as shown at 51, and is adapted to engage a cam member 52 on the bracket 28 so that when the sheared-off portion 51 engages the cam 52 it will elevate the arm 24 and move the pawl 26 out of engagement with the teeth 16.

A gear 55 is secured to a shaft 56 and this shaft is connected at one end with a clutch member 57 while the other end of the shaft has a manipulating knob 13a secured thereto for manually rotating the shaft and the platen 44.

A second clutch member 59 is secured to a shaft 12 and this shaft is connected to the platen 44. A spring 61 maintains the clutch members 57 and 59 in operative relation but will permit sliding movement of the clutch members for a purpose which will be presently explained.

The sleeve 46 is provided with a lug 62 which is hinged at 63 on the sleeve so that the lug may maintain its vertical position in one direction of movement of the platen 44 but which may be moved on its pivot when the platen is shifted in the opposite direction.

A punch 64 is carried at one end of a lever 65 70 pivoted on a bracket 66 secured to a frame 10, as

shown more particularly in Figs. 7 and 8. This lever is provided with a cam member 67 which is adapted to be engaged by the hinged lug 62 when the platen is moved automatically by the typewriting apparatus to the left, as shown by the arrow in Fig. 6, thereby causing one end of the lever 65 to be depressed and consequently elevating the punch 64 so that it will produce a perforation in the paper 43. The position of the platen when the paper is punched is shown in 10 dotted lines in Figure 7.

The operation of the device shown in Figs. 1 to 9, inclusive, is as follows: The sheet of paper is placed in the bookkeeping machine, as shown in Fig. 2, with the lower end of the sheet being inserted. The lever 21 is then moved to the right, as shown in Fig. 2, and as indicated by the arrow, and this movement will cause a slight depression of the spring 25 and movement of the arm 24 in the same direction. The arm 30, however, moves 15 in the opposite direction and the pivoted lugs 31 engage a crank 32, causing said crank to be rocked whereby the crank 35 will engage the enlargement 36 on the rod 37 and shift it to the right, causing the pins 41 to be moved away from the paper 43 and out of the perforations 42 in the paper and the perforation or opening 47 in the sleeve 46 if the pin has been received by the aligned perforations. It will be appreciated, however, that when the paper is inserted in a downward manner, that the pins 41 have not been received by a perforation due to the fact that these perforations are always located adjacent the last line on which an item has been placed by the typewriting machine. When the sheared off portion 30 35 of the arm 24 has moved away from the cam 52, the spring 29 will pull the arm 24 toward the gear 16 so that the pawl 26 will engage the teeth of the gear so that further movement of the arm 21 will cause rotation of the gear and likewise 40 the platen 44, due to the meshing of the gears 16 and 55. At this time, the pawl 31 has moved away from the crank 32, thereby releasing the rod 37 and permitting the spring 48 to shift the arm to the left in Fig. 2 so that the pin 41 will 45 again come in contact with the sheet 43.

If the perforation 42 in the sheet 43 has not registered with the passage or perforation 47 in the sleeve 46, it will again be necessary to rock the lever to the right in Fig. 2 as previously until the perforations are aligned and the pin will slip into said perforations and retain the cylinder and sheet against further movement. If however, the perforations are aligned and the pin has been received by said aligned perforation during the movement of the lever 21 and the rotation of the gears 16 and 55 the paper will not be torn due to the fact that the clutch members 57 and 59 which are frictionally engaged are permitted to slip on 55 each other and thus prevent further rotation of the platen 44.

Each time the arm 21 is released the spring 27 will return the arm to its normal inoperative position so that the arm 24 will ride over the cam 52 65 and have its pawl 26 released from the gear 16. Upon return movement of the arm 21, the hinged lug 31 on the arm 30 will ride over the crank 32 and thus the rod 37 will be maintained stationary.

Just before the sheet of paper 43 is removed from the machine after all of the items have been placed on the sheet, the platen 44 through the usual typewriting mechanism, or manually, is moved to the end of the line so that the hinged lug 70 75

62 will engage the cam 67 on the lever 65 and rock said lever whereby the punch 64 will be moved upwardly and towards the sheet of paper and platen until the punch moves through a perforation 64a in the sleeve 46, thereby providing a new perforation so that when the sheet is again removed from the bookkeeping book and returned to the machine it will be possible to operate the lever 21 after the lower end of the paper has been inserted sufficiently until the perforation 42 in the paper 43 aligns with the perforation 47 in the sleeve 46, whence the pin 41 will be in position to be received by the aligned perforation and retain the sheet of paper against further movement. It will be seen by this construction that the device positively rotates the sheet of paper so that items may be typed on the next line without necessitating the operator to attempt to determine the proper position of the paper for the application of the items.

A modified form of the construction is shown in Figs. 11 to 18, inclusive. In this instance, the lever 21a is loosely mounted upon the shaft 17 so that the pawl 26 will rotate the gear 16 through the medium of the arm 24 and the rocking of the lever 21.

The short arm 22a of the lever extends from the bell crank 20a and depending from the short arm 22a is a rod 70 pivotally mounted at 71 on the free end of the arm 22a. The rod 70 is provided with a fork 70a adapted to receive pins 72 projecting in opposite directions from the lever 73.

The lever 73 is pivotally mounted at 74, adjacent one end, on a bracket 75 secured to the inner face of the cylinder 46. The lever at this point is curved and is provided with a slot 76 through which is adapted to project a stop or pin 77.

A sleeve 78 is supported at 79 on a bracket 80 secured to the inner face of the sleeve 46. A spring 81 tends to force the pin 77 outwardly of the sleeve 78 and through an opening 82 formed in the sleeve or cylinder 46.

The pin 77 is located in the slot 76 at one end of the lever 73 and lugs 83 on the pin 77 rest upon the curved surface 73a of the lever 73. The lever 73 passes through a slot 84 formed in the sleeve or cylinder 46.

The remaining parts of the device shown in Figs. 11 to 18, inclusive, have not been described since they are identical with the similarly located elements of Figs. 2 to 10, inclusive.

When the lever 21a is reciprocated to the right in Fig. 12, the arm 24 moves off the cam member 52 so that the pawl 26 will engage the teeth of the gear 16. Further movement of the lever will cause rotation of the gear 16 and likewise the gear 55 with a consequent rotation of the platen 44. Before the gear 16 is rotated, however, the rod 70 is elevated, permitting the spring 90 to move the outer end of the lever 73 upwardly thereby lowering the inner end and permitting the pin 77 to move outwardly through the passage 82 so that it will pass through the perforations 82 in the cylinder 46 and the opening 91 formed in the sheet of paper 92 which had been previously cut by a punch 93 mounted on one end of the lever 65.

It will be noted that the sheet of paper 92 instead of being punched with the round perforations 42 as shown in the sheet of paper 43 (Fig. 10), square portions 94 are cut from the sheet 92 as shown by dotted lines in Fig. 18. Thus the punch 93 has two blades at right angles to each other for the purpose.

Since the barrel or sleeve 78 is pivotally mounted at 79 on the bracket 80, this barrel is adapted to oscillate so that when the lever 73 is raised the pins 83 which project from opposite sides of the pin or stop 77 will move down over the rounded portion 73a of the lever 73 to permit the stop 77 to move outwardly of the opening 82 and maintain the stop in operative position.

The upper end of the barrel 78 is provided with a pawl 96 which is adapted to normally engage the teeth 97 of a wheel 98 which is secured to the shaft 12 connected with the platen 44. This maintains the platen stationary when the pin or stop 77 has projected through the opening 82 of the sleeve 46 and the opening in the paper 92 to prevent tearing of the paper when the lever 21a is moved, tending to rotate the gear 16. The clutch members 59 and 57 permit slippage so that the platen 44 may be held stationary when the gear 16 is rotated.

In this construction, as in previous constructions, the lever 21a is permitted to move through an angle so that the lever 73 may be permitted to release the pin 77 from the aligned passages before the gear 16 is revolved to operate the gear 55.

The knob 13a is employed for originally positioning the sheets of paper within the bookkeeping machine.

In Figs. 2 to 10, inclusive, it will be seen that the paper is inserted from the front portion of the platen 44 while in the construction shown in the remaining figures it is adapted to be inserted from the rear of the platen.

When the lever 73 is oscillated as previously described, the inner free end will bear against the lower portion of the barrel 78 and since this barrel is tilted at an angle inwardly towards the slot 76 of the lever 73, said lever will be rocked at a greater angle, causing the pawl 96 to become disengaged from the teeth of the toothed wheel 98 which is secured to the platen 44, thereby permitting the platen to be rotated in the usual manner.

Referring more particularly to Figs. 1 to 9, inclusive, it will be seen that the end of the platen which is enclosed within the sleeve 46 is provided with a groove 100 and upon opposite sides of this groove are secured to the platen toothed wheels 101 which are adapted to be engaged by lugs 102 shown more particularly in Figs. 8 and 9 formed integrally with the pin 41 so that when the lugs 102 engage the teeth of these wheels the platen will be held against rotation and the clutch members 57 will permit the platen to be held stationary while the gear 16 is rotated through the lever 21. This element, like the pawl 96 in Figs. 11 to 17, inclusive, retains the platen against rotation and thus prevents tearing the paper after the pins have engaged the respective cut-out portions in the paper.

The barrel 78 is provided with slots 78a in which the pins 83 ride.

I claim:

1. In a bookkeeping machine, a device for pre-determining the position of a sheet of paper in the machine and comprising means for punching a perforation in the paper at a point in said paper where a line of typing is to be applied, means adapted to be received by the perforation for retaining the sheet of paper in position for the addition of a new line of typing, means for progressively moving the paper through the machine, a platen adapted to frictionally engage and move the paper through the machine, means for

progressively rotating the platen, means operatively connecting the platen moving means with the perforation receiving means for causing said means to be released from the perforation before the platen is rotated, the last-mentioned means including a gear and a lever carrying a pawl, said pawl adapted to engage the teeth of the gear after the lever has been moved through a predetermined angle, said lever being directly connected with the perforation-receiving means, and means for actuating the punching means.

2. In a bookkeeping machine, a device for pre-determining the position of a sheet of paper in the machine and comprising means for punching a perforation in the paper at a point in said paper where a line of typing is to be applied, means adapted to be received by the perforation for retaining the sheet of paper in position for the addition of a new line of typing, a platen 15 adapted to frictionally engage and move the paper through the machine, a fixed sleeve receiving one end of the platen and provided with an opening adapted for alignment with the perforation in the paper, a spring pressed pin adapted to drop into the opening when the perforation 20 in the paper has been aligned with said opening, means for releasing the pin from the opening and including means for revolving the platen 25 after the pin has been released, the last-mentioned means including a gear and a lever carrying a pawl, said pawl adapted to engage the teeth of the gear after the lever has been moved through a predetermined angle, said lever being directly connected with the pin releasing means, 30 and means for actuating the punching means, 35

3. In a bookkeeping machine, a device for pre-determining the position of a sheet of paper in the machine and comprising means for punching a perforation in the paper at a point in said paper where a line of typing is to be applied, means adapted to be received by the perforation for retaining the sheet of paper in position for the addition of a new line of typing, a platen for moving the paper through the machine, means for holding the paper and platen against movement when a line of typing is being applied to the paper, means for removing the holding means out of operative relation with the platen and paper when the platen is to be revolved, means co-operatively connected with the last-mentioned means for causing rotation of the platen after the holding means has been released, the last-mentioned means including a gear and a lever carrying a pawl, said pawl adapted to engage the teeth of the gear after the lever has been moved to a predetermined angle, said lever being directly connected with the means for removing the holding means for the paper, and means for actuating the punching means.

65 4. In a bookkeeping machine, a device for pre-determining the position of a sheet of paper in the machine and comprising means for punching a perforation in the paper at a point in the paper where a line of typing is to be applied, a platen adapted to be revolved for moving the paper through the machine, a pin adapted to be received by the perforation, cooperating means on the pin and platen for holding the platen against rotation, means for moving the pin and the platen and including means for rotating the platen after the pin has been released, said last-mentioned means including a gear and a
70 lever carrying a pawl, said pawl adapted to en-

gage the teeth of the gear after the lever has been moved to a predetermined angle, said lever being directly connected with the moving means for the pin, and means for actuating the punching means.

5. In a bookkeeping machine, a device for pre-determining the position of a sheet of paper in the machine and comprising means for punching a perforation in the paper at a point in the paper where a line of typing is to be applied, a platen adapted to be revolved for moving the paper through the machine, a pin adapted to be received by the perforation, cooperating means on the pin and platen for holding the platen against rotation, means for moving the pin out of engagement with the perforation and for causing release of the platen and including a lever, means actuated by the lever after the pin has been removed for causing rotation of the platen, the last-mentioned means including a gear, a rod carrying a pawl and directly connected with the lever, said pawl adapted to engage the teeth of the gear after the lever has been moved through a predetermined angle, said lever being directly connected with the means for moving the pin out of engagement with the perforation, and means for actuating the punching means. 10 15 20 25

means for actuating the punching means.
6. In a bookkeeping machine, a device for pre-determining the position of a sheet of paper in the machine and comprising means for punching a perforation in the paper at a point in the paper where a line of typing is to be applied, a platen adapted to be revolved for moving the paper through the machine, a pin adapted to be received by the perforation, cooperative means on the pin and platen for holding the platen against rotation, means for releasing the pin from the perforation in the paper, means for actuating the releasing means and including a lever, intermeshing gears for causing rotation of the platen, a pawl carried by the lever and adapted to engage the teeth of a gear for causing rotation of the gear after the lever has been moved through a predetermined angle for causing release of the pin, and means for actuating the punching means.

7. In a bookkeeping machine, a device for pre-determining the position of a sheet of paper in the machine and comprising means for punching a perforation in the paper at a point in the paper where a line of typing is to be applied, a platen adapted to be revolved for moving the paper through the machine, a pin adapted to be received by the perforation, cooperative means on the pin and platen for holding the platen against rotation, means for releasing the pin from the perforation in the paper, means for actuating the releasing means and including a lever, intermeshing gears for causing rotation of the platen, a pawl carried by the lever and adapted to engage the teeth of a gear for causing rotation of the gear after the lever has been moved through a predetermined angle for causing release of the pin, means for actuating the punching means, and means for retaining the pawl in an inoperative position while the lever has been moved through the predetermined angle. 50 55 60 65

8. In a bookkeeping machine, a device for predetermining the position of a sheet of paper in the machine and comprising means for punching a perforation in the paper at a point in the paper where a line of typing is to be applied, a platen adapted to contact with the paper at all times and adapted to be revolved for moving 75

the paper through the machine, a pin adapted to be received by the perforation, cooperating means on the pin and platen for holding the platen against rotation, means for releasing the pin and 5 for moving the platen and including means for rotating the platen after the pin has been released, means for causing the pin to be released

Just before the platen is rotated, means for actuating the punching means, and means to permit slippage of the rotating means for the platen when cooperating means between the pin and the platen has locked the platen against rotation. 5

JOSEPH H. LOEB.
